FLUID FLOW CONTROL DEVICE

Russell B. Matthews, Wauwatosa, Wis., assignor to Baso Inc., Milwaukee, Wis., a corporation of Wisconsin

Application April 25, 1955, Serial No. 503,680

16 Claims. (Cl. 137—66)

The present invention pertains to improvements in fluid flow control devices and is particularly directed to devices for use in controlling fuel flow in fuel burning apparatus wherein it is desired to have ignition of a pilot burner as a prerequisite to affording fuel flow to a main burner, and wherein it is also desired to have all fuel flow to both burners automatically shut off on extinguishment of the flame at said pilot burner, to thereby provide a safety shut-off of the entire apparatus.

It is a general object of the present invention to provide an improved fluid flow control device of the character set forth wherein control of fluid flow by both a safety shut-off device and by a manually operable plug valve is provided in a single compact device as distinguished from the large or several devices heretofore required for such control.

Another object of the invention is to provide an improved control device of the character described wherein the safety shut-off device is disposed coaxially within a plug type valve member to afford the aforementioned compactness and to permit disposition of manual resetting means for said device and manual operating means for said plug valve member in close proximity to each other to facilitate manual actuation thereof.

Another object is to provide a control device of the character described wherein the safety shut-off means provides main burner fuel flow interruption during resetting and 100% safety shut-off of the fuel, and the plug valve member is actuatable to interrupt all fuel flow as desired to thereby shut-off all of the burners independently of said safety shut-off device.

A more specific object is to provide a device of the character set forth wherein the safety shut-off device comprises an electromagnet and coacting armature, there being means fixed to said device to permit said plug valve to be rotated without causing rotation of said shut-off device, thereby protecting the lead connections for said electromagnet.

Another specific object is to provide a fluid flow control device of the class described wherein the electromagnet and armature are both movable, movement of said armature to said magnet providing actuation of a pilot valve to afford fuel flow to a pilot burner for ignition thereof, retraction of said armature coupled to said magnet moving a main fuel valve to open position for fuel flow to both a main burner and said pilot burner, said plug valve providing manual shut-off of all fuel flow to both of said burners independently of said main and pilot valves.

Another object of the invention is to provide an improved control device of the character set forth wherein actuation of the resetting mechanism holds the main fuel valve of the safety shut-off device and a pilot fuel valve closed, and also holds an auxiliary pilot fuel by-pass valve open, whereby fuel flow to only the pilot burner is permitted during resetting, continuation of pilot fuel flow upon release of the reset mechanism being dependent

2

upon actuation of said main and pilot fuel valves to open position on said release, the construction of said safety shut-off device being such that the main fuel valve cannot be opened unless the pilot burner is ignited.

- 5 Another object of the invention is the provision in a control device of the character set forth, of a valve body having main and pilot fuel passages interconnected downstream from the main fuel valve so that fuel flow through both of said passages is controlled by said main valve, 10 there being an auxiliary passage communicating with said main fuel passage upstream of said main valve and a double acting pilot valve interposed in said pilot fuel and auxiliary passages, said pilot valve including a normally closed first valve member in said auxiliary passage and a connected normally open second valve member in said pilot fuel passage, pilot fuel flow being initiated by movement of said first valve member to open position, to permit pilot fuel flow through said auxiliary passage into said pilot fuel passage, said second member 15 being simultaneously moved to closed position to prevent fuel flow through said pilot fuel passage to the main burner through the main fuel passage downstream of said valve seat, subsequent opening of said main valve providing fuel flow to said main burner through said main passage, and return of said first and second valve members to their normal positions providing pilot fuel flow into said pilot fuel passage past said normally open second valve member as long as said main valve is open.
- 20 30 The novel features which I consider characteristic of my invention are set forth with particularity in the appended claims. The device itself, however, both as to its organization and mode of operation, together with additional objects and advantages thereof, will best be 25 understood from the following description of a specific embodiment when read in connection with the accompanying drawing, in which:

Figure 1 is a sectional view of a flow control device embodying the present invention and schematically showing the control device connected to main and pilot burners and to a thermoelectric generator;

Figure 2 is a fragmentary top view of the device of Figure 1 showing the various operating positions of the plug valve and operating means therefor; and

45 Figure 3 is an enlarged fragmentary vertical sectional view of a portion of Figure 1 showing the structural details of the double acting pilot fuel valve.

Like reference characters indicate corresponding parts throughout the several views of the drawings.

50 Referring to Figure 1, numeral 10 designates a valve body formed with an inlet chamber 12, an outlet chamber 14 and an intermediate chamber 16. Contiguous sections of a conduit 18 for supplying fuel to a main burner 20 are connected to the valve body 10 in communication with inlet chamber 12 and outlet chamber 14. The valve body 10 is further formed with a pilot fuel passage 22 comprising a passage 22a and pilot fuel outlet chamber 22b separated by a pilot valve chamber 22c. Fuel is supplied to a pilot burner 26 through a fuel supply conduit 55 24 fixed to valve body 10 in communication with pilot outlet chamber 22b, said pilot burner being disposed in igniting proximity to the main burner 20 as shown in Figure 1.

The valve body 10 is formed also with a relatively 60 large tapered bore 28 for receipt of a frusto-conically shaped plug valve 30. Although I prefer to employ a rotatable plug valve 30 having substantially the shape shown in Figure 1, it is believed readily apparent that rotatable valve members of other shapes and configurations may be used, it merely being necessary for the present invention, that valve 30 and the bore in which it is seated have complementary surfaces to provide gas

tight seating engagement therebetween and that valve member 30 be movable between several controlling positions within valve body 10.

A cover plate 32 fastened to valve body 10 by any appropriate means such as screws 34, is utilized to enclose opening 28; said cover plate 32 being formed with an opening 32a for extension therebeyond of an operating handle 30a for plug valve 30. Coiled compression spring 36 is interposed between plate 32 and plug valve 30 for maintaining said valve 30 in seating engagement with the surface of the bore 28. Plug valve 30 is formed with a coaxial opening 30c opening into the intermediate chamber 16 and is further formed with a valve port 30b for selectively affording communication between the inlet chamber 12 and said intermediate chamber, as will hereinafter appear in the discussion of the operation of the present invention.

An electromagnetic power unit 38 is disposed within the opening 30c of the plug valve 30 and comprises an enclosure 39 having an end wall 39a to which a U-shaped electromagnet core member 40 is rigidly fixed as by any well known means such as valve stem 42. A valve member 44 is pivotally mounted on the valve stem 42 and cooperates with a valve seat 46 to control the flow of fuel between the intermediate chamber 16 and the outlet chamber 14. The power unit 38 also comprises an energizing winding 48 wound about the leg portions of the U-shaped core member 40. One end of the winding 48 is grounded to the valve stem 42, and the other end is fixed to a lead connector 49 which extends through an opening in the end wall 39a and is connected in circuit with a terminal 50 insulatedly extending through a wall portion of the valve body 10 and having a portion exposed within an external connector socket 85 as shown in Figure 1. Mounted adjacent pilot burner 26, is a thermoelectric generator 52 shown schematically in Figure 1 and having a hot junction 52a and cold junctions 52b; said thermoelectric generator being connected in circuit with terminal 50 and hence with electromagnet winding 48 through a conductor 86.

The enclosure 39 has a centrally apertured end wall 39b opposite the end wall 39a and fixed in the aperture thereof is a grommet or bearing 58. An armature stem 56 is axially slidable in the bearing 58, and fixed thereto within the enclosure 39 is an armature 54 which is co-operable with the electromagnet core 40. A reset button 60 is rigidly fixed to the armature stem 56 and is axially slid able in a bore 87 extending axially through the handle portion 30a of the plug valve 30. In order to prevent escape of fluid fuel around reset button 60, I prefer to employ an O-ring 88 within a groove therefore in the bore 86 as shown in Figure 1.

The pilot valve chamber 22c is provided with valve seats 62 and 64, the latter being formed in valve body 10. The valve seat 62 preferably surrounds a central aperture 89 in a plug 90 threaded into one end of the chamber 22c and separating the latter from the intermediate chamber 16. The aperture 89 functions as an auxiliary pilot fuel by-pass passage as will hereinafter appear. Disposed within the chamber 22c is a cup-shaped double acting valve member 70 comprising connected valve members 66 and 68 which cooperate respectively with the seats 62 and 64. The valve members 66 and 68 are alternatively engageable with their respective valve seats. Interposed between valve members 70 and valve body 10 is a compression spring 72 biasing the valve member 66 toward engagement with valve seat 62 and biasing the valve member 68 away from the valve seat 64. A compression spring 74 having a spring strength greater than that of compression spring 72 is positioned within the valve member 70 as shown in Figure 1 for a purpose which will hereinafter appear.

Rigidly secured to armature stem 56 is an L-shaped cam or actuating member 76 having an extended portion 76a disposed for reciprocatory sliding movement in a

longitudinal groove 91 formed in the bore 30c. In one position of the plug valve member 30 the portion 76a of member 76 is aligned with the aperture 89 and is movable therethrough into engagement with the spring 74 for actuation of the double acting pilot valve 70 during depression of the reset button 60.

Interposed between cam member 76 and the end wall 39b of enclosure 39 is compression spring 78 which biases the armature 54 and the electromagnetic core 40 toward separated relation and provides firm seating engagement of the valve member 44 on the seat 46 whenever said armature and core member are in separated relation. The spring 78 also biases the member 76 and the reset button 60 toward the released positions shown. A compression spring 80 which is substantially weaker than the spring 78 is interposed between valve body 10 and the end wall 39a of enclosure 39 to move the valve member 44 to flow-permitting position and the member 76 and reset button to released positions upon release of said reset button following depression of the latter and electromagnetic coupling of armature member 54 and core member 40.

In order to prevent twisting and possible breakage of the lead connector 49, I prefer to employ stop means in the form of a tang 82 fixed to the enclosure 39 and having an end portion positioned within a slot 10a formed in valve body 10 to prevent rotation of the enclosure 39 irrespective of rotation of plug valve 30.

Further, I prefer to employ indicator means such as pin 84 fixed to plug valve 30 and movable within a slot 32b formed in the cover plate 32 to indicate to an operator the position of said plug valve 30.

The operation of the embodiment of the invention shown in the drawing is as follows:

With plug valve 30 and each of valve members 44 and 66 in flow-preventing position, all fuel flow to the main and pilot burners is shut off, and the first step in affording ignition of the pilot burner 26 and main burner 20, is to rotate plug valve 30 until pin 84 engages the end of slot 32b designated "reset-on." In this position of plug valve 30 fuel is permitted to flow to intermediate chamber 16 through inlet chamber 12 and valve port 30b; and the portion 76a of the actuating member 76 is aligned with the aperture 89. Thereafter, in order to afford fuel flow to the pilot burner 26 for ignition thereof, it is merely necessary to manually depress the reset button 60, thereby moving the valve member 66 to its flow-permitting position and causing the armature member 54 to be moved to its attracted position with respect to electromagnet core member 40 against the bias of spring 78. Fuel can now flow from intermediate chamber 16 through the aperture 89, pilot valve chamber 22c, pilot outlet chamber 22b, and conduit 24 to pilot burner 26, where it may be ignited in any well known manner. Depression of reset button 60, in addition to opening valve member 66 moves the valve member 68 to its flow-preventing position to prevent fuel flow from pilot valve chamber 22c to main burner 20 through passage 22a and outlet chamber 14. The aforementioned movement of valve members 66 and 68 is afforded by depressing engagement of the extended portion 76a of cam member 76 with compression spring 74 whereby the manual force exerted on reset button 60 is transmitted to valve member 70. The spring 74 permits the extended portion 76a to continue to move following seating of the valve member 68 on the seat 64, thereby insuring firm contact between armature 54 and electromagnet core member 40 as the latter are reset to attracted position by depression of the button 60.

Ignition of the fuel at the pilot burner 26 causes the flame thereof to heat the hot junction 52a of thermoelectric generator 52, whereupon the latter generates an electric current which flows through electromagnet winding 48 and effects magnetic coupling of the armature member 54 and core member 40 which are in attracted

relation. Release of reset button 60 while the armature and core member are thus coupled permits the compression spring 80 to move said coupled armature and core member axially within the plug 30 to retracted position (not shown) and to simultaneously move the valve member 44 to its flow-permitting position. Movement of armature to its retracted position returns the valve member 66 to its flow-preventing position and the valve member 68 to its flow-permitting position. However, in order to maintain continuous fuel flow to pilot burner 26 throughout the aforementioned retractile movement of the armature, the valve member 44 is moved to its flow-permitting position prior to return of the valve member 66 to its flow-preventing position.

With the reset button 60 in its released position and the coupled armature and core in retracted positions, fuel is permitted to flow from the intermediate chamber 16 into the outlet chamber 14, and through the pilot fuel passage 22 and conduit 24 to the pilot burner 26. Fuel also flows from the outlet chamber 14 through the conduit 18 to main burner 20, and the fuel emitted at the main burner 20 is ignited by the flame of the pilot burner 26. The fuel burning apparatus utilizing the subject invention is thereby placed in operating condition.

Upon extinguishment of the flame of the pilot burner 26, hot junction 52a of thermoelectric generator 52 is cooled by the surrounding atmosphere, thereby deenergizing electromagnet winding 48 and reducing the attractive force generated thereby, whereupon the compression spring 78 overcomes said attractive force and the force of the compression spring 80 and returns the core member 40 to separated relation with respect to armature member 54 and valve member 44 to seating engagement with valve seat 46, thereby terminating fuel flow to both of said main and pilot burners.

If it is desired to render the fuel burning apparatus inoperative independently of the main fuel valve 44 and pilot fuel valve 70, for example while pilot burner 26 is ignited, it is merely necessary to rotate plug valve 30 by means of the operating handle 36a so that pin 84 is aligned with the designation "off." In this position of the plug valve 30 communication between inlet chamber 12 and intermediate chamber 16 is interrupted, and all fuel flow to both pilot burner 26 and main burner 20 is shut off.

Although I have shown and described certain specific embodiments of my invention, I am fully aware that many modifications thereof are possible. My invention, therefore, is not to be restricted except insofar as is necessitated by the prior art and by the spirit of the appended claims.

What is claimed as the invention is:

1. In a fluid flow control device, in combination, first and second flow control members each being movable between controlling positions, operating means for said control members, comprising a first movable member operatively associated with said first flow control member, a second movable member operatively associated with said second flow control member, said movable members being biased to separated relation, said first movable member being movable against said bias from an initial position to a second position in attracted relation with respect to said second movable member to effect movement of said first control member from one to another of its controlling positions, means for coupling said first and second movable members when in said attracted relation, means biasing said coupled members toward the initial position of said first movable member to effect by movement of said coupled members under said bias, movement of said second control member from one to another of its controlling positions and return of said first control member to its said one controlling position, a control valve formed with an opening within which said operating means is positioned, and means in said opening associated with said control valve and said first movable member to

render the latter inoperative to effect movement of said first control member from one to another of its controlling positions with movement of said first movable member from its initial position to its second position except when said control valve is in a predetermined one of its controlling positions.

2. In a fluid flow control device, in combination, a valve body, first and second flow control members within said body each being movable between controlling positions, operating means for said control members, comprising a first movable magnetic member operatively associated with said first flow control member, a second movable magnetic member operatively associated with said second flow control member, said magnetic members being biased to separated relation, said first magnetic member being movable against said bias from an initial position to a second position in attracted relation with respect to said second magnetic member to effect movement of said first control member from one to another of its controlling positions, an energizing winding on one of said magnetic members energizable to couple said first and second magnetic members when in said attracted relation, means biasing said coupled magnetic members toward the initial position of said first magnetic member to effect by movement of said coupled magnetic members under said bias, movement of said second control member from one to another of its controlling positions and return of said first control member to its said one controlling position, a rotatably operable control valve formed with an opening within which said operating means is positioned, and means in said opening associated with said control valve and said first magnetic member to render the latter inoperative to effect movement of said first control member from one to another of its controlling positions with movement of said first magnetic member from its initial position to its second position except when said control valve is in a predetermined one of its controlling positions.

3. In a fluid flow control device, in combination, a valve body, first and second flow control members within said body each being movable between controlling positions, operating means for said control members, comprising a first movable member operatively associated with said first flow control member, a second movable member operatively associated with said second flow control member, said movable members being biased to separated relation, said first movable member being movable against said bias from an initial position to a second position in attracted relation with respect to said second movable member to effect movement of said first control member from one to another of its controlling positions, means for coupling said first and second movable members when in said attracted relation, means biasing said coupled members toward the initial position of said first movable member to effect by movement of said second control member from one to another of its controlling positions and return of said first control member to its said one controlling position, a rotatably operable control valve having an opening formed symmetrically of the axis of rotation of said valve, said operating means being positioned within said opening, means in said opening associated with said control valve and said first movable member to render the latter inoperative to effect movement of said first control member from one to another of its controlling positions with movement of said first movable member from its initial position to its second position except when said control valve is in a predetermined one of its controlling positions, and means preventing relative rotational movement between one of said movable members and said valve body during rotational movement of said valve.

4. In a fluid flow control device, in combination, a valve body, first and second flow control members within said body each being movable between controlling positions,

operating means for said control members, comprising a first movable magnetic member operatively associated with said first flow control member, a second movable magnetic member operatively associated with said second flow control member, said magnetic members being biased to separated relation, said first magnetic member being movable against said bias from an initial position to a second position in attracted relation with respect to said second magnetic member to effect movement of said first control member from one to another of its controlling positions, an energizing winding on one of said magnetic members including circuit connection means fixed to said valve body and energizable to couple said first and second magnetic members when in said attracted relation, means biasing said coupled magnetic members toward the initial position of said first magnetic member to effect by movement of said coupled magnetic members under said bias, movement of said second control member from one to another of its controlling positions and return of said first control member to its said one controlling position, a rotatably operable control valve having an opening formed symmetrically of the axis of rotation of said valve, said operating means being positioned within said opening, means in said opening associated with said control valve and said first magnetic member to render the latter inoperative to effect movement of said first control member from one to another of its controlling positions with movement of said first magnetic member from its initial position to its second position except when said control valve is in a predetermined one of its controlling positions, and means interposed between said valve body and said operating means preventing relative rotational movement between said one of said magnetic members and said valve body during rotational movement of said valve to prevent undue strain on said energizing winding circuit connection means during such movement of said valve.

5. In a fluid flow control device, in combination, a valve body having first, second and auxiliary fluid passages, a first flow control member for control of fluid flow through said first and second fluid passages, a second flow control member in said second fluid passage biased to flow-permitting position, an auxiliary flow control member in said auxiliary fluid passage biased to flow-preventing position, operating means for said control members, comprising a first movable member operatively associated with said first flow control member, a second movable member operatively associated with said second and auxiliary flow control members, said movable members being biased to separated relation whereby said first flow control member is biased to flow-preventing position, said second movable member being movable against said bias from an initial position to a second position in attracted relation with respect to said first movable member to effect movement of said second control member from flow-permitting to flow-preventing position and said auxiliary control member from flow-preventing to flow permitting position, means for coupling said first and second movable members when in said attracted relation, means biasing said coupled members toward the initial position of said second movable member to effect by movement of said coupled members under said bias, movement of said first control member from flow-preventing to flow-permitting position, return of said second control member to its flow-permitting position and return of said auxiliary control member to its flow-preventing position, a rotatably operable control valve in said valve body having an opening formed symmetrically of the axis of rotation of said valve, said operating means being positioned within said opening, actuating means on said valve for effecting movement of said second movable member to its said second position and for effecting rotational movement of said control valve independently of said control members, means in said opening associated with said control valve and said

10 second movable member to render the latter inoperative to effect movement of said second and auxiliary control members with movement of said second movable member from its initial position to its second position except when said control valve is in a predetermined one of its controlling positions, and means interposed between said valve body and said operating means preventing relative rotational movement between one of said movable members and said valve body during rotational movement of said valve.

15 6. In a fluid flow control device, in combination, a valve body having first, second and auxiliary fluid passages, a first flow control member in said first and second fluid passages, a second flow control member in said second fluid passage biased to flow-permitting position, an auxiliary flow control member in said auxiliary fluid passage biased to flow-preventing position, operating means for said control members, comprising a first movable magnetic member operatively associated with said first flow control member, a second movable magnetic member operatively associated with said second and auxiliary flow control members, said movable magnetic members being biased to separated relation whereby said first flow control member is biased to flow-preventing position, said second magnetic member being movable against said bias from an initial position to a second position in attracted relation with respect to said first magnetic member to effect movement of said second control member from flow-permitting to flow-preventing position and said auxiliary control member from flow-preventing to flow-permitting position, an energizing winding on one of said magnetic members energizable to couple said first and second magnetic members when in said attracted relation, means biasing said coupled magnetic members toward the initial position of said second magnetic member to effect by movement of said coupled magnetic members under said bias, movement of said first control member from flow-preventing to flow-permitting position, return of said second control member to its flow-permitting position and return of said auxiliary control member to its flow-preventing position, a rotatably operable control valve formed with an opening within which said operating means is positioned, means in said opening associated with said control valve and said second magnetic member to render the latter inoperative to effect movement of said second and auxiliary control members with movement of said second magnetic member from its initial position to its second position except when said control valve is in a predetermined one of its controlling positions, and actuating means on said valve for effecting movement of said second magnetic member to its said second position and for effecting rotational movement of said control valve independently of said flow control members.

20 7. In a fluid flow control device, in combination, a valve body having first, second and auxiliary fluid passages, a first flow control member in said first and second fluid passages, a second flow control member in said second fluid passage biased to flow-permitting position, an auxiliary flow control member in said auxiliary fluid passage biased to flow-preventing position, operating means for said control members, comprising a first movable electromagnet member operatively associated with said first flow control member, a second movable electromagnet member operatively associated with said second and auxiliary flow control members, said movable electromagnet members being biased to separated relation whereby said first flow control member is biased to flow-preventing position, said second electromagnet member being movable against said bias from an initial position to a second position in attracted relation with respect to said first electromagnet member to effect movement of said second control member from flow-permitting to flow-preventing position and said auxiliary control member from flow-preventing to

flow-permitting position, an electromagnet winding on one of said electromagnet members including circuit connection means fixed to said valve body and energizable to couple said first and second electromagnet members when in said attracted relation, means biasing said coupled electromagnet members toward the initial position of said second electromagnet member to effect by movement of said coupled electromagnet members under said bias, movement of said first control member from flow-preventing to flow-permitting position, return of said second control member to its flow-permitting position and return of said auxiliary control member to its flow-preventing position, a rotatably operable control valve formed with an opening within which said operating means is positioned, means in said opening associated with said control valve and said second electromagnet member to render the latter inoperative to effect movement of said second and auxiliary control members with movement of said second electromagnet member from its initial position to its second position except when said control valve is in a predetermined one of its controlling positions, actuating means on said valve for effecting movement of said second electromagnet member to its said second position and for effecting rotational movement of said control valve independently of said flow control members, and means interposed between said valve body and said operating means preventing relative rotational movement between said one of said electromagnet members and said valve body during rotational movement of said valve to prevent undue strain on said electromagnet circuit connection means during such movement of said valve.

8. In a fluid flow control device, in combination, a valve body having first, second and auxiliary fluid passages, a first flow control member for control of fluid flow through said first and second fluid passages, a second flow control member in said second fluid passage biased to flow-permitting position, an auxiliary flow control member in said auxiliary fluid passage biased to flow-preventing position, operating means for said control members, comprising a first movable member operatively associated with said first flow control member, a second movable member operatively associated with said second and auxiliary flow control members, said movable members being biased to separated relation whereby said first flow control member is biased to flow-preventing position, said second movable member being movable against said bias from an initial position to a second position in attracted relation with respect to said first movable member to effect movement of said second control member from flow-permitting to flow-preventing position and said auxiliary control member from flow-preventing to flow-permitting position, means for coupling said first and second movable members when in said attracted relation, means biasing said coupled members toward the initial position of said second movable member to effect by movement of said coupled members under said bias, movement of said first control member from flow-preventing to flow-permitting position, return of said second control member to its flow-permitting position and return of said auxiliary control member to its flow-preventing position, a rotatably operable control valve in said valve body having an opening formed symmetrically of the axis of rotation of said valve, said operating means being positioned within said opening, means in said opening associated with said control valve and said second movable member to render the latter inoperative to effect movement of said second and auxiliary control members with movement of said second movable member from its initial position to its second position except when said control valve is in a predetermined one of its controlling positions, and means interposed between said valve body and said operating means preventing relative rotational movement between one of said movable members and said valve body during rotational movement of said valve.

9. In a fluid flow control device, in combination, a valve body having first, second and auxiliary fluid passages, a first flow control member for control of fluid flow through said first and second fluid passages, a second flow control member in said second fluid passage biased to flow-permitting position, an auxiliary flow control member in said auxiliary fluid passage biased to flow-preventing position, operating means for said control members, comprising a first movable member operatively associated with said first flow control member, a second movable member operatively associated with said second and auxiliary flow control members, said movable members being biased to separated relation whereby said first flow control member is biased to flow-preventing position, said second movable member being movable against said bias from an initial position to a second position in attracted relation with respect to said first movable member to effect movement of said second control member from flow-permitting to flow-preventing position and said auxiliary control member from flow-preventing to flow-permitting position, means for coupling said first and second movable members when in said attracted relation, means biasing said coupled members toward the initial position of said second movable member to effect by movement of said coupled members under said bias, movement of said first control member from flow-preventing to flow-permitting position, return of said second control member to its flow-permitting position and return of said auxiliary control member to its flow-preventing position, a rotatably operable control valve in said valve body having an opening formed symmetrically of the axis of rotation of said valve, said operating means being positioned within said opening, and means in said opening associated with said control valve and said second movable member to render the latter inoperative to effect movement of said second and auxiliary control members with movement of said second movable member from its initial position to its second position except when said control valve is in a predetermined one of its controlling positions.
10. A fluid flow control device comprising, a rotatable plug valve member formed with a cavity, first and second flow control members each movable to controlling positions, operating means for said first flow control member comprising cooperable relatively movable coupling members disposed within said cavity, said coupling members having separated relation and being movable to coupled relation, one of said coupling members being operatively associated with said second control member for moving the latter from one to another of its controlling positions by relative movement of said coupling members toward coupled relation, and means in said cavity associated with said plug valve member and said one coupling member for rendering the latter inoperative to effect movement of said second control member toward its said other controlling position except when said plug valve member is in a predetermined position of rotation.
11. A fluid flow control device comprising, a rotatable plug valve member formed with a cavity, first and second flow control members each movable to controlling positions, safety shut-off means for said first flow control member comprising cooperable relatively movable magnetic coupling members disposed within said cavity, said coupling members being biased toward separated relation and one of said coupling members being manually resettable against said bias into coupled relation with the other coupling member, said one coupling member being operatively associated with said second control member for moving the latter from one to another of its controlling positions by resetting movement of said one coupling member, and means in said cavity associated with said plug valve member and said one coupling member for rendering the latter inoperative to effect movement of said second control member toward its said other controlling position except when said plug valve member is in a predetermined position of rotation.
12. A fluid flow control device comprising, a rotatable plug valve member formed with a cavity, first and second flow control members each movable to controlling positions, safety shut-off means for said first flow control member comprising cooperable relatively movable magnetic coupling members disposed within said cavity, said coupling members being biased toward separated relation and one of said coupling members being manually resettable against said bias into coupled relation with the other coupling member, said one coupling member being operatively associated with said second control member for moving the latter from one to another of its controlling positions by resetting movement of said one coupling member, and means in said cavity associated with said plug valve member and said one coupling member for rendering the latter inoperative to effect movement of said second control member toward its said other controlling position except when said plug valve member is in a predetermined position of rotation.

12. A fluid fuel flow control device comprising a valve body formed with a plug receiving bore, a plug valve member rotatably seated in said bore and formed with a cavity, a valve member movable to controlling positions, operating means for said valve member comprising a pair of cooperable relatively movable coupling members disposed within said plug cavity, means affording a connection between said coupling members and said plug valve member tending to cause rotation of both of said coupling members with said plug valve member, and means for preventing rotation of one of said coupling members with rotation of said plug valve member.

13. A fluid fuel flow control device comprising a valve body formed with a plug receiving bore, a plug valve member rotatably seated in said bore and formed with a cavity, a valve member movable to controlling positions, operating means for said valve member comprising a pair of cooperable relatively movable coupling members disposed within said plug cavity, means affording a connection between said coupling members and plug valve member tending to cause rotation of both of said coupling members with said plug valve member, one of said coupling members being provided with electrical connection means, and means for preventing rotation of said one coupling member with rotation of said plug valve member and thereby affording protection to said electrical connection means.

14. A fluid fuel flow control device comprising a valve body formed with a plug receiving bore, a plug valve member rotatably seated in said bore and formed with a cavity, a valve member movable to controlling positions electromagnetic operating means for said valve member comprising cooperable electromagnet and armature coupling members disposed within said plug cavity and relatively movable coaxially of said plug valve member to attracted and retracted positions, means affording a connection between said coupling members and said plug valve member tending to cause rotation of both of said coupling members with rotation of said plug valve member and means for preventing rotation of one of said electromagnet and armature members with rotation of said plug valve member.

15. A fluid fuel flow control device comprising a valve body formed with a plug receiving bore and with a valve seat substantially coaxial therewith, a plug valve member rotatably seated in said bore and formed with a cavity, a valve member cooperable with said seat, safety shut-off means for said valve member comprising an electromagnet and a cooperable armature disposed within

5. said plug cavity and relatively movable coaxially of said plug valve member, said electromagnet being fixed to said valve member for movement of the latter rectilinearly therewith toward and away from said seat, means affording a connection between said safety shut-off means and said plug valve member tending to cause rotation of said armature and electromagnet with rotation of said plug valve member, and means for preventing rotation of said electromagnet with rotation of said plug valve member.

10. 16. In a fluid flow control device, in combination, a valve body, first and second flow control members within said body each being movable between controlling positions, operating means for said control members, comprising a first movable member operatively associated with said first flow control member, a second movable member operatively associated with said second flow control member, said movable members being biased to separated relation, said first movable member being movable against said bias from an initial position to a second position in attracted relation with respect to said second movable member to effect movement of said first control member from one to another of its controlling positions, means for coupling said first and second movable members when in said attracted relation, means biasing said coupled members toward the initial position of said first movable member to effect by movement of said coupled members under said bias, movement of said second control member from one to another of its controlling positions and return of said first control member to its said one controlling position, a rotatably operable control valve having an opening formed symmetrically of the axis of rotation of said valve, said operating means being positioned within said opening, means affording a connection between said movable members and said rotatable valve tending to cause rotation of both of said movable members with rotation of said rotatable valve, and means preventing relative rotational movement between one of said movable members and said valve body during rotational movement of said valve.
